VISE ASSEMBLY

A. T. Porterfield, Wilmar Township,
Los Angeles County, Calif.

Application March 22, 1945, Serial No. 584,154

4 Claims. (Cl. 90—60)

1

My invention relates to a vise whose two work-engaging members are operatively connected to one another, not directly, as in the case of usual vises, but indirectly thru the medium of a third member.

An object and advantage is the provision, in my novel vise, of adaptability to work whose maximum jaw-flanked dimension, although beginning with the smallest and ranging thru the more frequently encountered ones, exceeds by many times the maximum jaw-flanked dimensions handled by vises of conventional type and much larger and heavier than mine.

Another object and advantage, when the above referred to third member consists of the T-slotted base of a machine tool, made to function as the backbone of my vise assembly, is the considerable saving in initial cost when compared with the cost of even the largest obtainable conventional vise.

A still further object and advantage resident in the above combination with a machine tool base or bed is the ease, the speed and the relative safety with which my vise assembly may be installed, handled and removed, all derivable from the small size and small weight of the vise components.

Additional objects and advantages manifest themselves thruout this description of the particular embodiment which was selected for clear and convenient exposition of the principles of the instant invention from a number of other conceivable embodiments that can and will readily suggest themselves to persons skilled in the art. This embodiment, a simple and typical vise assembly, is illustrated in the accompanying drawings, in which—

Figure 1 is an isometric view of said vise assembly, a special sub-base or sub-bed having been incorporated, intervening between the two jaws of the vise assembly, on the one hand, and the long, longitudinally T-slotted, regular base or bed of a machine tool, on the other hand.

Figure 2 is a partly sectional plan view from above of the two jaws of said vise assembly, the base or bed being removed.

Figure 3 is a side view of the above, only the relative position of the base or bed being indicated.

In Figure 1, a machine tool of the class wherein a long, longitudinally T-slotted base constitutes a regular or standard component, conceivably a milling machine for example, is fragmentarily indicated by 48, said long base, provided with longitudinally extending T-slots 30 and 31, being

2

indicated by 10A. Secured thereto, by means of said T-slots and of three bolts, 32, 33 and 34, and their respective nuts, 36, 37 and 38, and of the corresponding fourth bolt and nut, not visible but indicated by 35 and 39, is the long, longitudinally T-slotted sub-base or sub-bed 10, to whose T-slots, 49 and 50, are secured the work-engageable sub-assembly 11 and the work-engageable, base-securable member or jaw 12 by means of four sets of bolts and nuts, two of which sets being indicated by 42, 44 and 41, 43, the two respective slots being indicated by 25 and 27, the other two slots being indicated in Figure 2 by 26 and 28. Jaw 12 is provided with a replaceable face or face plate 24. Contributively constituting said sub-assembly 11 is the jaw-mount 13.

Referring to Figure 3, it will be seen how jaw 12 and sub-assembly 11 are secured to milling machine base 10A directly and without the medium of the intervening sub-base 10 that appears in Figure 1. Continuing to refer to Figures 1 and 3 and particularly to Figure 2, sub-assembly 11 is seen to comprise the three main members consisting of the already referred to base-securable jaw-mount 13, the base-free jaw 15 and the base-free-jaw-engaging tightening screw 14, whose square-sectional end 17 is adapted to engagement thereof by a wrench and whose helically threaded section is indicated by 16. Jaw 12 and base 10A, or, alternately, sub-base 10, constitute the other two main members in the total of five main members which are regarded as mainly constituting the vise assembly.

Jaw-mount 13 is provided with the bore 46, also referred to as a race, adapted to snugly receive therewithin and guide the hollow ram 45, fixed to the face or face plate 47, which two sections together constitute the functionally integral, already referred to base-free jaw 15, which may be originally integral or it may be constituted by welding sections 45 and 47 to one another. The interior wall defining the recess in ram 45 may be helically threaded, or, as shown in Figure 2, a non-therewith-integral internally disposed part, such as brass nut 21, press-fitted therein and locked with a setscrew, threaded correspondingly to the helical thread of screw 14 for receiving it. An integral flange 18 receives the thrust on screw 14, bearing on the jaw-mount thru brass washer 19. Opposed to flange 18 is the collar 20 pinned to screw 14 at 29. The plane of symmetry of sub-assembly 11, which is also that of ram 45 and screw 14, is indicated by 55 PS—PS. Although the liberal transverse dimen-

sion of the ram and a snug fit thereof in bore 46 condition, when the parts are new or have been newly adjusted, plane-of-symmetry-parallel travel of the ram when it is reciprocated or longitudinally displaced, additional guidance therefor is provided by the two plane-of-symmetry-flanking guide elements or guide bolts 22 and 23, each thereof being screwed into face or face plate 41 and slidable in a wall of the jaw-mount 13, the heads of the two bolts functioning as stops, abutting against said wall, whereby accidental disengagement of the base-free jaw 15 from the jaw-mount is precluded.

I claim:

1. A vise assembly including a plurality of T-slot-engaging bolts and at least five main members consisting of: a long, longitudinally T-slotted base provided with a plurality of T-slots; a thereof longitudinally adjustably disposable, work-engageable, base-securable jaw; a work-engageable base-free jaw; a base-securable jaw-mount adapted to mount said base-free jaw in a manner whereby adjustable displacement thereof may be effected relatively to said jaw-mount and longitudinally of said base; and a base-free-jaw-engaging tightening screw, axially in the plane of symmetry of said jaw-mount and adapted to operatively intervene between it and said base-free jaw; each of the two said base-securable members being adapted to be secured by means of said T-slots and said bolts to said base at any desired one of a plurality of loci successively distributed longitudinally of said base and independently of the locus of the other said base-securable member.

2. A vise assembly including a plurality of T-slot-engaging bolts and at least five main members consisting of: a long, longitudinally T-slotted base provided with a plurality of T-slots; a thereof longitudinally adjustably disposable, work-engageable, base-securable jaw; a work-engageable base-free jaw; a base-securable jaw-mount adapted to mount said base-free jaw in a manner whereby adjustable displacement thereof may be effected relatively to said jaw-mount and longitudinally of said base; and a base-free-jaw-engaging tightening screw, axially in the plane of symmetry of said jaw-mount and adapted to operatively intervene between it and said base-free jaw; each of the two said base-securable members being adapted to be secured by means of said T-slots and said bolts to said base at any desired one of a plurality of loci successively distributed longitudinally of said base and independently of the locus of the other said base-securable member; said base-free jaw mainly consisting of a work-contacting face and a thereto fixed hollow ram having a bore inside of which there is an internal helical thread corresponding to the thread of said screw and adapted to receive it for said displacement of said base-free jaw; said jaw-mount being recessed to provide thereat a ram-receiving, ram-guiding race; said base-free jaw and said jaw-mount being provided with at least two therebetween engaging, plane-of-symmetry-flanking guide bolts for additionally directing said displacement, each of said bolts being screwed into said face and slidable in a wall of said jaw-mount in a manner whereby the head of said bolt functions as a stop, abutting against said wall.

3. A vise assembly including a plurality of T-slot-engaging bolts and at least five main members consisting of: a long, longitudinally T-slotted base provided with a plurality of T-slots; a thereof longitudinally adjustably disposable, work-engageable, base-securable jaw; a work-engageable base-free jaw; a base-securable jaw-mount adapted to mount said base-free jaw in a manner whereby adjustable displacement thereof may be effected relatively to said jaw-mount and longitudinally of said base; and a base-free-jaw-engaging tightening screw, axially in the plane of

symmetry of said jaw-mount and adapted to operatively intervene between it and said base-free jaw; each of the two said base-securable members being adapted to be secured by means of said T-slots and said bolts to said base at any desired one of a plurality of loci successively distributed longitudinally of said base and independently of the locus of the other said base-securable member; said base-free jaw mainly consisting of a work-contacting face and a thereto fixed hollow ram having a bore inside of which there is an internal helical thread corresponding to the thread of said screw and adapted to receive it for said displacement of said base-free jaw; said jaw-mount being recessed to provide thereat a ram-receiving, ram-guiding race; said base-free jaw and said jaw-mount being provided with at least two therebetween engaging, plane-of-symmetry-flanking guide elements for additionally directing said displacement.

4. A vise assembly including a plurality of T-slot-engaging bolts and at least five main members consisting of: a long, longitudinally T-slotted base provided with a plurality of T-slots; a thereof longitudinally adjustably disposable, work-engageable, base-securable jaw; a work-engageable base-free jaw; a base-securable jaw-mount adapted to mount said base-free jaw in a manner whereby adjustable displacement thereof may be effected relatively to said jaw-mount and longitudinally of said base; and a base-free-jaw-engaging tightening screw, axially in the plane of symmetry of said jaw-mount and adapted to operatively intervene between it and said base-free jaw; each of the two said base-securable members being adapted to be secured by means of said T-slots and said bolts to said base at any desired one of a plurality of loci successively distributed longitudinally of said base and independently of the locus of the other said base-securable member; said base-free jaw mainly consisting of a work-contacting face and a thereto fixed hollow ram having a bore inside of which there is an internal helical thread corresponding to the thread of said screw and adapted to receive it for said displacement of said base-free jaw; said jaw-mount being recessed to provide thereat a ram-receiving, ram-guiding race; said base-free jaw and said jaw-mount being provided with at least two therebetween engaging, plane-of-symmetry-flanking guide bolts for additionally directing said displacement, each of said bolts being screwed into said face and slidable in a wall of said jaw-mount in a manner whereby the head of said bolt functions as a stop, abutting against said wall.
